UNITED STATES PATENT OFFICE.

WILLIAM I. BUNKER, OF LA GRANGE, ILLINOIS.

DESIGN FOR A SADDLE-CUSHION.

SPECIFICATION forming part of Design No. 28,039, dated December 14, 1897.

Application filed October 27, 1897. Serial No. 656,587. Term of patent 14 years.

To all whom it may concern:

Be it known that I, WILLIAM I. BUNKER, a citizen of the United States, residing at La Grange, in the county of Cook and State of Illinois, have invented and produced a new and useful Design for Saddle-Cushions, of which the following is a specification.

In the accompanying drawings, Figure 1 is a perspective view showing the under side of a cushion for bicycle-saddles, illustrating my design; Fig. 2, a similar view showing the upper side of the cushion, and Fig. 3 a cross-section taken on line 3 of Fig. 2.

The leading feature of my design consists in a body having a narrow extending front or pommel portion and a broad rear or seat portion and having open cellular work on its up-

per side throughout substantially its entire area, the under side being closed or covered.

A is the body portion, having a narrow extending front or pommel portion and a broad rear or seat portion proper, and B an edge or border surrounding the same, the body portion being provided with cellular work, as shown in Figs. 2 and 3, and the whole presenting a harmonious and ornate figure, as shown in the drawings.

I claim—

The design for a saddle-cushion, substantially as shown and described.

WILLIAM I. BUNKER.
